(No Model.)

W. C. MOORE.

ROTARY CORN POPPER.

No. 389,316.

Patented Sept. 11, 1888.

UNITED STATES PATENT OFFICE.

WILLIAM C. MOORE, OF SPRINGFIELD, MISSOURI.

ROTARY CORN-POPPER.

SPECIFICATION forming part of Letters Patent No. 389,316, dated September 11, 1888.

Application filed April 30, 1888. Serial No. 272,239. (No model.)

To all whom it may concern:

Be it known that I, WILLIAM C. MOORE, of Springfield, in the county of Greene and State of Missouri, have invented a new and Improved 5 Rotary Corn-Popper, of which the following is a full, clear, and exact description.

This invention relates to corn-poppers, and has for its object to provide a corn-popper so constructed that it may be easily handled and 10 will be effective in operation.

The invention will be set forth in the following description, and pointed out in the claims.

Reference is to be had to the accompanying drawings, forming a part of this specification, 15 in which similar figures of reference indicate corresponding parts in all the views.

Figure 1 illustrates the invention. Fig. 2 is a horizontal section on line *x-x*, Fig. 1. Fig. 3 is a detail view of the end of the shaft, and 20 Fig. 4 is a perspective view of the end of the fastener.

In the construction of the popper I employ a rod or shaft, 1, of a length sufficient to permit the person operating the popper to be at a distance from the fire. The shaft 1 is formed with a crank-handle, 2, and has located thereon, adjacent to handle 2, a supporting-handle, 3, of wood or other suitable material, which is a slow conductor of heat, by means of which the popper 25 may be conveniently held in position for use and the shaft 1 rotated. The receptacle to hold the corn is formed of wire, and may be made of any suitable shape. As here shown, an oblong receptacle, 4, is employed, substantially 30 cylindrical in shape and formed in two parts, 5, having their meeting edges 6 re-enforced by a metal binding, 6', folded and crimped thereon, and additionally secured by rivets, if desired. The outer ends of the parts 5 of the 35 receptacle, through which the rod 1 passes, are strengthened by metallic disks 7, secured thereto by projections 8, which are bent through the meshes of the wire. The outer end of shaft 1 is formed with a screw-threaded 40 shouldered end, 9, which projects through the disk 7. The outer portion 5 of the receptacle is fixed on the shaft 1 by a washer, 10, on the inside of disk 7, between it and the shoulder 11 of screw-threaded end 9, and by a 45 nut, 12, on the latter. The inner portion 5 of the receptacle is provided with a cross-piece, 50

13, at its open end, which supports the latter on rod 1, and is movable endwise on the latter to open and close the receptacle. To hold the inner portion 5 in closed position a suitable fastening device is employed, and, as here shown, consists of a rod, 14, forming a spring-arm and having one end bent around rod 1, as at 15, and abutting against holder 3, and the other end formed with a folded projection, 16, 60 and a hook, 17, which engages the shaft 1 and abuts against the end of inner portion 5 when the latter is in closed position. The rod 14 is sufficiently flexible for the hook 17 to be engaged and disengaged with the rod 1 and to 65 be raised up for the inner portion 5 to be moved back on shelf 1 when the receptacle is to be opened.

The inner portion 5 may be held in opened position by means of the folded projection 16 70 engaging the edge thereof. In the construction of the hopper no solder is used, so that the parts will not become separated.

The several parts, being detachable, may be easily taken apart and a number of poppers 75 packed up in compact shape for sale or transportation.

The operation of the popper will be readily seen. The receptacle being closed, as shown in Fig. 1, the holder 3 is grasped in one hand 80 and the receptacle rotated by means of the crank-handle 2 in the other.

While I have described a specific construction of parts, I do not intend to limit myself thereto, as they may be varied without departing from the essential features of the invention.

Having thus described my invention, what I claim as new, and desire to secure by Letters Patent, is—

1. A rotary corn-popper consisting of a receptacle mounted on a shaft and formed with a fixed portion and a portion movable endwise on the shaft, a fastener for holding the movable portion in open and closed position, the shaft having a crank-handle, and a loosely-mounted supporting-handle, substantially as described.

2. A corn-popper consisting of shaft 1, with crank-handle 2 and supporting-handle 3, 100 loosely mounted on shaft 1, a wire receptacle consisting of the parts 5, with re-enforced

edges 6, and supporting-disks 7, with projections 8 engaging the wire-netting, the outer portion 5 being secured to shaft 1 by a washer, 10, on the screw-threaded end 9 thereof, and by a nut, 12, engaging the latter, and the spring-arm 14, secured to shaft 1 and having hook end 17, with folded projection 16

for holding the endwise movable inner portion 5 in open and closed position, substantially as described.

WILLIAM C. MOORE.
